Primary Examiner — Janice Hallmark*(74) Attorney, Agent, or Firm* — McGarry Bair PC(57) **CLAIM**

The ornamental design for a ceiling fan blade iron, as shown and described.

DESCRIPTION

FIG. 1 is a bottom perspective view of a ceiling fan blade iron showing my new design in the environment of a ceiling fan;

FIG. 2 is a top perspective view of the ceiling fan blade iron of FIG. 1 with the environment of a ceiling fan removed; FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The ceiling fan shown in broken line in FIG. 1 depicts environmental subject matter and forms no part of the claimed design. All other broken lines illustrate portions of the ceiling fan blade iron that form no part of the claimed design.
